DISPENSER FOR HOT BEVERAGES

Newton A. Blickman, Pearl River, N.Y., assignor to
S. Blickman, Inc., Weehawken, N.J., a corporation of
New York

Filed Dec. 28, 1960, Ser. No. 63,370

Term of patent 7 years

(Cl. D2—3)

FIG. 1.

FIG. 2.

FIG. 3.

FIG. 4.

FIG. 5.

FIGURE 1 is a perspective view of the dispenser for hot beverages embodying my new design,

FIG. 2 is a top plan view thereof,

FIG. 3 is a side elevational view thereof, the opposite side being a mirror image of this disclosed side,

FIG. 4 is a rear elevational view thereof, and

FIG. 5 is a perspective view of the faucet element on an enlarged scale.

The dominant features of my design reside in the portions shown in full lines.

I claim:

The ornamental design for a dispenser for hot beverages substantially as shown and described.
